10

The present invention relates to an automatic distributor or feeder, for sample carriers for X-ray diffractometers.

The distributor according to this invention is intended to assure the automatic removal of a sample carrier at the end of its analysis in a diffractometer, the transfer of a sample carrier of a sample to be analysed from a storage area to the diffractometer and its centering and its gripping against the movable diffractometer stop, in such a way that the sample carrier follows the movements of said movable stop.

To this end, the distributor forming the subject of this invention is characterized in that it comprises, on the one hand, a supporting cradle for the carriers of the samples to be analysed, this cradle being mounted so as to be freely movable about an axis situated in the plane of the smooth surface of the sample, this axis being identical with the axis of rotation of the movable diffractometer stop, and on the other hand, automatic means for controlling the disengagement of the support cradle from the diffractometer stop, the removal of the carrier of an analysed sample and the leading of a new sample carrier unto the support cradle.

According to one embodiment of the support cradle, it is constituted by a piece presenting a flat face designed to receive a carrier for a sample to be analysed and a cylindrical face having a semi-circular cross-section mounted in a shell having a corresponding shape and in which the support cradle can freely pivot.

According to one embodiment of the means for disengaging the cradle support from the diffractometer stop, the cylindrical shell having a semi-circular cross-section is mounted so as to be able to pivot around a pin carried by a shaft which is slidable in a vertical direction.

According to one embodiment of the automatic control means of the distributor, these means are constituted by a mechanical assembly associated on the one hand, with a sliding shaft carrying the shell and the support cradle and, on the other hand, with a storage area, or magazine, containing the carriers of samples to be analysed and a storage area receiving the carriers of samples already analysed, this mechanical assembly comprising, in combination:

an arbor driven into rotation by a motor controlled by a pulse signalling the end of the operation of said diffractometer, this arbor carrying a cam and an eccentric roller;

a first lever mounted in a pivoting manner around a fixed axis, one end of this lever being pivotally mounted on the sliding shaft and the other end of this lever being subjected to the action of this cam in opposition to an elastic restraining element;

a second lever in which is arranged an oblong slot for housing the eccentric roller, this second lever being articulated at one of these extremities, on a third lever pivotally mounted about a stationary axis, the other end of the second lever carrying a shoe slidably mounted along a slide and pivoting between two limiting positions, one of these positions corresponding to a projection of the shoe beyond the slide such that

2

this projection encounters an edge of a sample carrier contained in the magazine for carriers of samples to be analysed in order to transfer it by the slide unto the support cradle and the other of these positions corresponding to a retracting of the shoe in order to return it to the rear; and

a fixed stop on which the semi-circular shell comes to bear at the time of the descent of the sliding shaft which carries it, this stop being disposed in such a manner as to provoke the rocking of the shell against an elastic restraining element and the resultant sliding of the carrier of the sample already analysed into a chute leading it to a receiving magazine, the various movements of the mechanical assembly being combined to produce the following operations at the end of an analysis: the leading of the sample carrier into a horizontal position; then the lowering of the sliding shaft, the rocking of the shell and the ejection of the carrier of the sample analysed; re-elevation of this sliding shaft; re-alignment and remounting of the shell to a level corresponding to that of the loading slide; driving, by the shoe, of a carrier of a sample to be analysed to the support cradle; return of the shoe to its rest position, the exposed face of the sample carrier then being in contact with the diffractometer stop and being centered thereon.

These and other objects, features and advantages of the present invention will become more readily understood from the following detailed description when taken together with the attached drawings, in which:

FIGURE 1 is an elevation view of the distributor, and

FIGURE 2 is a cross-sectional view taken along the plane II—II of FIGURE 1.

The figures show, in dotted lines, a diffractometer stop 1, the stop being movable around a horizontal axis 2 situated in the plane of the exposed surface of a sample to be analysed supported by a sample carrier 3.

This sample carrier is placed on the flat face 4a of a support cradle 4, the cradle presenting a cylindrical face 4b having a semi-circular cross-section and resting through the intermediary of roller bearings 6, in a shell 5 having a complementary shape.

The axis of the half-cylinder of shell 5 is coaxial with the axis 2 when support cradle 4 presses sample carrier 3 against stop 1.

Shell 5 is pivotally mounted around the axis of a pin 7 carried on a shaft 8 disposed in such a manner as to slide in a longitudinal direction in two slides 9a and 9b. A spring 10 tends to maintain the shell 5 in the position shown in the drawings.

A lever 11 is pivotally mounted around a fixed axis 12; one end of this lever is articulated on shaft 8; its other end carries a roller 11a; an elastic element such as a spring (not shown) exerts a force on the lever 11 in such a manner as to constantly urge shaft 8 upwardly.

A support 13 carrying sliders 9a and 9b as well as axis 12, also carries an arbor 14 connected to a kinematic transmission (not shown) which drives it into rotation.

To arbor 14 is attached a cam 15 carrying an eccentric roller 16, cam 15 is continually in contact with follower 11a of lever 11 and its profile is shaped so as to provoke, during a complete revolution of arbor 14, the displacement movements of shaft 8 which will be described below.

Excentric roller 16 is maintained in a slot 17a formed in a second lever 17 articulated at one of its ends on a third lever 18 pivotally mounted for rotation about the axis of a pin 19 rigidly connected to support 13.

Lever 17 has its other end articulated on a shoe 20 mounted to slide along a slide 21.

Above this slide is disposed a removable storage maga-

zine 22 containing carriers of samples to be analysed. The arrangement of the sample carriers and the shoe are such that when the shoe moves in its forward sense (to the right in FIGURE 1) along slide 21, it pushes against the lowest sample carrier and pushes it along the slide while, when the shoe moves in the reverse direction, it is retracted downwardly and passes freely under magazine 22.

At another portion of the assembly a stop 23 is mounted either on support 13 or on slides 9a and 9b in such a way as to cause it to contact shell 5 when shaft 8 is driven downwardly, the purpose of this operation being explained below.

Finally, a chute 24 is rigidly mounted in an inclined manner on support 13, the lower end of this chute being positioned above a second magazine 25 provided to receive the carriers of samples already analyzed.

The above described assembly operates in the following manner: when the diffractometer has finished carrying out an analysis a pulse signaling the end of its operation initiates the rotation of arbor 14, for example in the direction of arrow F, the distributor being shown in the drawings to be in its rest, or retracted position.

Arbor 14, in turning, drives cam 15 carrying roller 16; cam 15 is shaped so as to cause lever 11, when moved by the cam, to urge shaft 8 downwardly; during the progress of this displacement. Support cradle 4 separates from stop 1, which permits it to return to a horizontal position due to its eccentric center of gravity. When shaft 8 arrives at its lower dwell point, shell 5 encounters stop 23, which provokes a rocking of the latter around the axis of its pin 7.

FIGURE 1 shows, in broken lines, the positions of cam 15, lever 11 and shell 5 when shaft 8 is at its lower dwell point.

Shell 5 is at that time tilted and the carrier of the analysed sample slides out of support cradle 5 and through chute 24 until falling into magazine 25.

As the rotation of arbor 14 continues, the cam 15 passes the position indicated in broken lines; lever 11, urged by its elastic restraining elements, pivots so as to move shaft 8 upwardly and shell 5 is separated from stop 23 and returns to its normal position under the action of spring 10. Shaft 8 continues to rise until the flat upper surface of support cradle 4 is even with the upper face of slide 21.

During this time, the rotation of arbor 14 drives roller 16 so as to provoke the pivoting of the assembly of levers 17 and 18; this pivoting serves to drive shoe 20 from its rest position, shown in solid lines, to its extreme forward position, shown in broken lines in FIGURE 1.

During the course of this movement, the end of shoe 20 projects above slider 21 and encounters the edge of the sample carrier located at the bottom of magazine 22; the sample carrier is extracted from the magazine and is pushed by the shoe on the slide until it slides into position on support cradle 4, the latter then being at the level of slide 21.

Then, when shoe 20 is retracted and returned to its rest position, shaft 8 mounts further until the sample carrier is pressed against stop 1, at which time a new analysis can be performed and arbor 14 is stopped until the completion of this analysis.

During the analysis, support cradle 4 follows completely the rotation of stop 1 around the common axis of rotation 2.

While one preferred embodiment of the present invention has been shown and described in detail in this specification, it should be apparent that many variations and modifications would occur to one skilled in the art without departing from the spirit of this invention and that its coverage should therefore be limited only by the scope of the appended claims.

We claim:

1. A distributor for sample carriers engageable with a

diffractometer stop which is rotatable about a fixed axis, comprising; a support cradle for carriers of samples to be analyzed, said cradle being mounted so as to be freely rotatable about an axis situated in the plane of a smooth surface of the samples carried by said carriers, said cradle being movable in a direction normal to the fixed axis of the diffractometer stop and between a retracted position spaced from the stop and a projected position with a sample carrier mounted thereon pressed into engagement with the stop with the axis of the cradle disposed coaxial with the fixed axis of the diffractometer stop, said cradle and a sample carrier mounted thereon being rotatable with said diffractometer stop about the coaxial axis of the cradle and stop when the sample carrier is pressed into engagement with the stop in said direction normal to the fixed axis of said stop, and automatic means for sequentially positioning a sample carrier to be analyzed on said cradle while it is spaced from the stop, for moving said cradle to said projected position with the sample carrier mounted thereon pressed into engagement with said stop for rotation about the cradle axis, for moving said cradle and sample carrier mounted thereon to said retracted position, and for removing said analyzed sample carrier from said cradle.

2. A distributor as recited in claim 1 wherein said cradle comprises; a piece presenting a flat face for receiving said sample carriers and a cylindrical face having a semi-circular cross-section; and wherein said distributor further comprises: a shell having a receiving surface having a shape corresponding to said cylindrical face of said cradle, said cradle being mounted in said shell with said cradle cylindrical face facing said shell receiving surface so that said cradle can freely pivot in said shell, said cylindrical face and said corresponding receiving surface being concentric with said axis of said cradle.

3. A distributor as recited in claim 2 further comprising: a shaft mounted so as to be slidable in a vertical direction; and a pin carried by said shaft and supporting said shell so that the latter can pivot around the axis of said pin, said pin extending in a horizontal direction and being disposed at right angles to the axis of said cradle.

4. A distributor according to claim 3, wherein said automatic means are constituted by a mechanical assembly associated with said shaft and with a first magazine holding carriers of samples to be analysed and with a second magazine for receiving carriers of samples already analysed, said mechanical assembly comprising:

an arbor rotatable through one revolution during each operation of said automatic means and carrying a cam having a roller mounted thereon and eccentric to the cam surface thereof;
a first lever pivotally mounted on a fixed axis, subject to the action of an elastic restraining element, having one end pivotally connected to said shaft and having its other end connected to be subjected to the action of said cam;
a second lever in which is arranged an oblong slot housing said eccentric roller;
a third lever having one end pivotally mounted on a stationary axis and its other end pivotally connected to one end of said second lever;
a shoe slidably mounted in a slide and being pivotably connected to the other end of said second lever, said shoe having a projecting portion and being pivotable between two limiting positions, in one of which said projecting portion projects above said slide for engagement with a sample carrier held in said first magazine for transferring it along said slide and onto said cradle and in the other of which positions said projecting portion is retracted so as to be unable to engage carriers held in said first magazine; and a fixed stop against which said shell comes to bear when said shaft descends and said cradle and shell are in the retracted position, said fixed stop being so arranged as to cause said shell to rock around said

pin, in opposition to a restraining force, so as to cause the carrier held in said cradle to slide into said second magazine; whereby said mechanical assembly functions to lead said sample carrier into a horizontal position, lower 5 said shaft, rock said shell so as to eject the carrier supported thereby, re-elevate said shaft, realign said shell so that the flat face of said cradle is even with said slide, move, by means of said shoe, a new sample onto said cradle, return said shoe to its 10 projected position with the exposed face of said carrier then being in contact with, and centered on, said rotatable stop.
